UNITED STATES PATENT OFFICE.

HENRY G. CORDLEY, OF GLEN RIDGE, NEW JERSEY.

DESIGN FOR A LIQUID COOLER AND DISPENSER.

42,166.

Specification for Design.

Patented Feb. 13, 1912.

Application filed November 3, 1911. Serial No. 658,452. Term of patent 14 years.

To all whom it may concern:

Be it known that I, HENRY G. CORDLEY, a citizen of the United States, residing at Glen Ridge, in the county of Essex, State of New Jersey, have invented a new, original, and ornamental Design for a Liquid Cooler and Dispenser, of which the following is a specification, reference being had to the accompanying drawings, forming a part hereof.

The figure is an elevation of a liquid cooler and dispenser showing my new de-

sign, the essential feature of which is a cooling chamber shaped to represent an orange resting on a cylindrical ring and surmounted by an inverted bottle of the shape shown.

I claim—

The ornamental design for a liquid cooler and dispenser, as shown.

HENRY G. CORDLEY.
